UNITED STATES PATENT OFFICE.

EDGAR MOTT BOTTOME, OF MOUNDSVILLE, WEST VIRGINIA, AND HAYDEN A. MARSHALL, OF CHICAGO, ILLINOIS, ASSIGNEES TO FOSTORIA GLASS COMPANY, OF MOUNDSVILLE, WEST VIRGINIA, A CORPORATION OF WEST VIRGINIA.

DESIGN FOR A DRINKING VESSEL OR SIMILAR ARTICLE.

42,350.

Specification for Design.

Patented Mar. 26, 1912.

Application filed January 30, 1912. Serial No. 674,399. Term of patent 14 years.

To all whom it may concern:

Be it known that we, EDGAR MOTT BOTTOME, a citizen of the United States, and residing at Moundsville, in the county of Marshall and State of West Virginia, and HAYDEN A. MARSHALL, of Chicago, in the county of Cook and State of Illinois, have invented a certain new, original, and ornamental Design for a Drinking Vessel or Similar Article, shown in the accompanying drawing, which is a view in perspective of the same.

We claim:—

The ornamental design for a drinking vessel or similar article, as shown.

EDGAR MOTT BOTTOME.
HAYDEN A. MARSHALL.
